UNITED STATES PATENT OFFICE.

JOHN G. RITZ, OF NEW YORK, N. Y.

AUTOMOBILE ENGINE-LOCK VALVE.

1,141,006.

Specification of Letters Patent. Patented May 25, 1915.

Application filed February 23, 1915. Serial No. 9,980.

To all whom it may concern:

Be it known that I, JOHN G. RITZ, a citizen of the United States, and a resident of the city of New York, borough of Brooklyn, in the county of Kings and State of New York, have invented a new and Improved Automobile Engine-Lock Valve, of which the following is a full, clear, and exact description.

10 This invention relates to improvements in safety devices, and particularly to an improved lock for gasoline engines used on automobiles and various other places where the engine and associated parts are adapted 15 to move from place to place.

The object in view is to provide an improved locking valve which will positively prevent the operation of the engine when the valve is in a locked position, the location 20 of the valve being such that the removal or tampering of the valve cannot be done with the hope of starting the engine.

Another object in view is to provide a valve and a lock therefor, the valve being 25 arranged in the mixture intake manifold or pipes of the engine in order that no successful bridging of the valve can be made.

In the accompanying drawings—Figure 1 is a fragmentary view of an automobile 30 engine showing an embodiment of the invention applied thereto; Fig. 2 is an enlarged vertical horizontal section through an embodiment of the invention, the same being taken on line 2—2 of Fig. 3; Fig. 3 is a sectional view through Fig. 2 taken on line 3—3; Fig. 4 is a view similar to Fig. 3, the parts being shown in a different position.

Referring to the accompanying drawings 40 by numerals, 1 indicates an engine of any desired kind provided with the usual manifold 2 for guiding the explosive mixture into the cylinders. The manifold 2 is supplied with a pipe 3 preferably comparatively short, and leading directly from the carbureter 4 which may be of any desired type. The carbureter 4 is supplied with gasoline or other fuel through pipe 5, which pipe extends to the supply tank arranged at 45 any suitable point. It will be observed that the gasoline or other fuel must be supplied to the carbureter 4, and after it has been carbureted the fuel passes through pipe 3 and through the casing 6 to the manifold 50 2, and from thence into the cylinders. The casing 6 as shown in Figs. 2, 3 and 4 is

merely a tubular structure provided with a laterally extending tubular portion 7 for receiving a lock 8. The casing 6 is provided with an enlargement 9 for receiving the end 60 of shaft 10, which shaft extends through the opposite side of the casing as shown in Fig. 2, and has connected therewith a pin 11. A butterfly valve 12 is rigidly connected with the shaft 10, and is limited in its 65 movement by pins 13 and 14 so that the valve may be correctly closed or opened. The disk or valve 12 is preferably fitted into a slot in shaft 10 and clamped therein in any desired manner, as for instance by a 70 suitable screw. This valve is of course in addition to the usual throttle valve associated with the carbureter 4, and is intended to be closed only when the engine has to be locked against operation.

75 The lock 8 may be of any desired type, as for instance of the Yale type provided with the usual tumblers and associated parts so that the rotating portion 15 must make a complete revolution before the key can be 80 removed. If the valve is unlocked the key may be readily inserted and must be turned a complete revolution before it can be removed, the revolution causing a locking action. The rotating portion 15 has connected 85 therewith at the inner end a segment 16 which is rotated with the rotating section, said segment being substantially one quarter of a circle so that when the lock is open the segment 16 will move three quarters of a 90 circle before the same engages pin 11. After the segment engages pin 11 it will force the same a quarter of a revolution before the key can be removed. It will be observed 95 that a quarter of a turn would be sufficient for opening or closing the butterfly valve 12, but the key cannot be removed from the rotating portion 15 except on a complete revolution, and therefore the segment 16 is provided which will be allowed a three 100 quarter's revolution free and then one quarter's revolution acting on the part either for closing or opening the valve 12.

105 It will be observed that the butterfly valve occupies a very small amount of space and therefore allows a full flow of explosive mixture from the carbureter into the engine, which would not be the case of an ordinary ground valve unless the valve is made an unreasonable size, which would be difficult 110 if not impossible to apply to pipe 3. It is to be noted that in automobiles the space for

applying attachments of this kind is very small, and in the present invention it is aimed to provide a casing which is substantially the same size as the pipe 3, though if desired the same may be slightly larger. The casing 6 is adapted to be frictionally secured in place by welding, brazing or other suitable means so that it cannot be removed without entirely disabling the engine. It is to be noted that the casing 6 and associated parts are arranged between the carbureter and the manifold and preferably as near the manifold as possible so that there will be no chance of bridging of the casing in case an unauthorized person should remove the same by sawing or breaking in any manner. Unauthorized persons have at different times removed valves and locks arranged in the gasolene feed pipe 5, and have bridged the broken part or valve by a flexible tube through which the gasolene freely flows. In some instances an unauthorized person has broken pipe 5 and connected a flexible tube therewith which in turn was connected with a supply provided by such unauthorized person, which supply may be arranged on the body of the automobile or at any convenient point while the unauthorized person starts the engine. By arranging the valve 12 in pipe 3 no supply of explosive matter can be supplied to the engine as it is necessary to pass the fuel through a carbureter before it can possibly be utilized in the cylinders of

the engine. Therefore, the location of the casing 6 and associated parts is important and presents the advantage of a structure which cannot be overcome by any of the practices heretofore used

What I claim is—

In a device of the character described, a casing provided with a drum and an upstanding housing, a butterfly valve arranged in said drum, stops arranged in the drum for limiting the movement of the valve, a shaft carrying said valve, one end of said shaft extending through the wall of said drum into said housing, a pin secured to the end of the shaft extending into the housing, and a lock in said housing provided with a rotary section requiring a complete rotation before the key can be withdrawn, and a segment rigidly secured to said rotary section, said segment being slightly less than a quadrant whereby the butterfly valve is held against movement in one direction by one of said stops and against movement in the opposite direction by said segment when the key is removed from said rotary section.

In testimony whereof I have signed my name to this specification in the presence of two subscribing witnesses.

JOHN G. RITZ.
